UNITED STATES PATENT OFFICE

ELMER D. McARTHUR, OF SCHENECTADY, NEW YORK, ASSIGNOR TO GENERAL ELECTRIC COMPANY, A CORPORATION OF NEW YORK

ELECTRIC HEATING APPARATUS

Application filed November 19, 1930. Serial No. 496,741.

My invention relates to electric heating apparatus, more particularly to electric heaters of the type in which the heat is generated in the heated body itself, and has for its object 5 simple, reliable and effective electric heating apparatus utilizing currents of high frequencies.

My invention has particular application to heating apparatus wherein the material or 10 body to be heated is placed between spaced electrodes electrically connected to a source of high frequency supply, whereby the body is heated by an electrostatic field. In the application of this type of heater it has been 15 found that the portion of the body adjacent the source of high frequency supply is heated with greater rapidity than the remaining more remotely situated portion. In accordance with my invention I provide in one form 20 thereof a series of pairs of heating electrodes with separate source of high frequency supply which are arranged on opposite sides of the pairs of plates, together with means for passing the body to be heated in succession 25 between the pairs of plates whereby it is heated uniformly.

My invention is especially useful in the heating of food products, such as milk and meat, for sterilization, cooking or other purposes. It has wide application, however, to 30 heating processes wherein a uniform rate of heating is desirable. This method of heating is to be distinguished from the usual method of heating in which heat is applied to the exterior of the body and must be transmitted by conduction into the interior portions. Such methods require a longer heating period and furthermore, the outer portions of the 35 body are subjected to the maximum temperature for a greater length of time than the interior portions, which is of especial disadvantage where the heating period is quite critical and must be closely controlled.

For a more complete understanding of my 40 invention reference should be had to the accompanying drawing in which Fig. 1 is a view showing in simplified partially diagrammatic form apparatus for applying high frequency current to the heating plates in accordance 45 with my invention, while Fig. 2 is a diagram-

matic representation of heating apparatus embodying my invention.

Referring to the drawing, in Fig. 1 I have shown a typical heating system comprising spaced electrodes, shown as plates 10 and 11 55 between which the material to be heated is placed, and a source of high frequency supply, shown as a three element electron discharge device or tube 12. The plates 10 and 11 are mounted on suitable electrically insulating supports (not shown). The material to be heated is placed between the plates in spaced or electrically insulated relation with them, for example in a suitable container 13 60 made of an electrically insulating material, such as glass.

It will be understood that the electron discharge device 12 operates in a manner similar to a high frequency short wave tube oscillator, such as used in radio transmission, and produces current of similar high frequencies, on the order of twenty to fifty million cycles per second. In the particular system shown the plates 10 and 11 are connected respectively 70 to the grid 14 and the anode or plate 15 of 75 the discharge device, suitable inductances 16 and 16a being included in the respective connections so as to form a resonant high frequency oscillation circuit. At these very high frequencies the inductance in the conductors 80 themselves may be sufficient to produce this desired resonant condition in which case no auxiliary inductance would be provided.

The filamentary cathode 17 of the discharge device is heated from a suitable source of alternating current which is connected to the cathode through a suitable transformer 18. Radio frequency coils 19 and 20 are included in the sides respectively of the cathode circuit. A tap 21 on the secondary of the transformer 18 leads through a grid leak resistance 22 and capacity 23 connected in parallel with each other, and through a choke coil 24 to the grid 14. A suitable source of 95 electrical supply, for example a direct current source of 500 volts or more, is connected to the tap 21 and the plate 15, a radio frequency choke coil 25 being included in the connection with the plate. The positive side 100

of the supply source is connected to the plate and the negative side to tap 21.

It will be understood that the frequency generated in the oscillation circuit including the two plates may be varied by changing the constants of the circuit, for example by varying the distance between the two plates 10 and 11. This adjustment will depend upon the rate of heating desired. The frequency used will depend upon the material to be heated. This method of heating is particularly useful in the uniform heating of articles which can not be heated by passing a current directly through them because of electrolytic action occurring at the electrodes. It also may be used in efficiently heating articles whose resistance is too high to be heated by the high frequency electromagnetic induction system in which the articles are placed inside of an electrical coil. It is very effective in the heating of various liquids, and materials containing moisture, such as articles of food including meats, vegetables, eggs, milk, etc., when for some reason it is undesirable to apply heat externally as from an hot oil bath or an oven. It may also be used in drying laundry.

In the use of the heating apparatus for some materials I have found that the electrode of each pair which is nearer the source of high frequency supply apparently has the greater heating effect, the portion of the material adjacent this electrode being heated more rapidly than the remaining portions. In the arrangement shown, the material adjacent the plate 10 is heated most rapidly. One explanation of this is the distortion of the electrostatic field due to the difference in the lengths of the conductors leading from the two plates to the source of supply. The plate 10 being nearer the source of high frequency supply constituted by the discharge device 12 has the shorter lead and consequently gives the greater heating effect since the lead to the other plate must pass the first plate and distorts the field due to its proximity.

As shown in Fig. 2, I provide in accordance with one form of my invention a plurality of pairs of plates 26 to 29 inclusive which are mounted preferably in equally spaced relation and with corresponding plates in alignment, together with suitable conveying means, such as a continuous conveyor 30 passing successively between the pairs of plates. The sources of high frequency supply 31 to 34 inclusive for the respective pairs of plates are placed on alternate opposite sides of the conveyor. It will be understood that the sources 31 and 34 are suitable sources of high frequency current, such as shown in Fig. 1, there being a separate source connected to each pair of plates. The material to be heated is passed on the conveyor in the containers 18 successively between the

pairs of plates and consequently the material in each container is subjected alternately on opposite sides to the higher rate of heating and as a result the material is heated uniformly throughout. It will be understood that the number of pairs of heating plates may be varied as desired to give the desired temperature and rate of heating.

While I have shown a particular embodiment of my invention, it will be understood, of course, that I do not wish to be limited thereto since many modifications may be made, and I, therefore, contemplate by the appended claims to cover any such modifications as fall within the true spirit and scope of my invention.

What I claim as new and desire to protect by Letters Patent of the United States is:

1. Electric heating apparatus comprising a plurality of pairs of electrodes, a separate source of high frequency supply for each of said pairs of electrodes, one of the electrodes of each pair giving a greater heating effect than the other, and means for passing the material to be heated between said pairs of electrodes in succession in such manner that different portions of said material are adjacent the electrode giving the greater heating effect whereby said material is heated uniformly.

2. Electric heating apparatus comprising a plurality of pairs of electrodes, a separate source of high frequency current supply for each of said pairs of electrodes, the electrodes of each pair being respectively closely and remotely situated with respect to their supply source, and means for passing the material to be heated between the electrodes of said pairs in succession in such manner that a given portion of the material is alternately adjacent said closely and remotely situated electrodes.

3. Electric heating apparatus comprising a plurality of pairs of electrodes, means for passing the material to be heated between the electrodes of said pairs in succession, a source of high frequency current for each of said pairs of electrodes, said sources being arranged on opposite sides of the path of travel of said material in such a manner that each of said sources is respectively closely and remotely situated with respect to its electrodes whereby a predetermined portion of said material passes adjacent the electrodes giving different rates of heating.

In witness whereof I have hereunto set my hand this 18th day of November, 1930.

ELMER D. McARTHUR.
